UNITED STATES PATENT OFFICE.

ROBERT F. WEEMS, OF BRIGHTON, AND EDWIN C. DUNBAR, OF WOLLASTON, MASSACHUSETTS, ASSIGNEES TO UNDERWOOD TYPEWRITER COMPANY, OF NEW YORK, N. Y., A CORPORATION OF DELAWARE.

TYPEWRITING MACHINE.

Application filed April 17, 1923. Serial No. 632,612.

This invention relates to typewriting machines, and more particularly to means for inserting into the machine a pack of work-sheets, the leading edge of which is so constituted that it is too thick to be inserted in the machine in the ordinary manner.

In certain trades, in practice, there is used a pack of work-sheets or cards for conveying uniformly prepared data from department to department. This pack may be made up of a plurality of cards of various weights, textures and colors, having similar forms. Some of them, especially the thin sheets, may have re-enforcing paper rings glued around filing-holes that are punched in their leading edges; others may have cords threaded through similar holes, and all of the cards along their leading edges are suitably bound together, as with wire staples, to keep them in registration. A heavy leading edge for the card-pack, which heretofore has been found too thick to insert into a typewriter, usually results, thus necessitating the writing of the cards by hand. One object of our invention is to provide means to make insertion of the pack into the machine practicable, so that all the data sheets may be typed simultaneously, the pack being capable of insertion into the machine and around the platen in substantially flat condition and caused to be fed or line-spaced in the usual manner by the feed-rolls which co-operate with the platen.

To accomplish these and other objects the platen is, in this instance, made displaceable upwardly in the platen-frame to a point where the bottom of the platen is about on a level with the top of the platen-frame or carriage, thus not only leaving a space between the bottom of the platen and the usual feed-rolls which run upon its under side, but also permitting the front and back of the platen-carriage frame to co-operate to serve as a rest or table upon which to lay the pack of cards and sheets, the leading end of the pack supported upon the front bar of the platen-carriage, and the bottom portion of the pack resting upon the rear bar of the platen-carriage. Thus the pack is readily laid between the platen and the feed-rolls. The platen when so elevated may remain geared to the usual line-spacing ratchet-wheel.

When the pack is thus inserted, it may be in straight condition, and to facilitate the bending or wrapping of the pack around the platen properly as the platen descends to typing position, there is arranged for co-operation with the platen a work-guide or support which occupies an elevated position just in front of the platen and may stand a little beneath the pack as the latter lies in flat condition upon the carriage frame. As the platen is pushed down, the pack is caught by and tucked down between the platen and said guide or support, and caused to wrap itself properly around the platen as the latter completes its descent to typing position, at which point the usual bottom feed-rolls serve to press the pack up against the bottom of the platen, to co-operate therewith in the subsequent line-feeding of the pack, or in the adjustment of the pack around the platen to bring it to position for typing the first line thereon. The space between said front work-guide or bar and the rear bar of the platen carriage is only a little in excess of the diameter of the platen itself, so that said front guide or bar co-operates with said rear paper-apron in bringing the pack, which is sometimes very stiff, to its proper position around the platen.

Said front work-guide or bar is preferably in the form of a feed-roll or rolls, so as to perform subsequent service in holding the pack back against the platen for the purpose of typing thereon, and also to aid in line-feeding the pack, especially after the bottom edge thereof has been advanced beyond the feed-rolls which run upon the platen.

Besides means for bending the pack around the platen, there are also provided means for "squaring" the pack, with the writing-lines on the work-sheets, parallel to the longitudinal axis of the platen, simultaneously with its insertion into the machine, means for holding the pack in its "squared" position at all times during a typing operation, and means for holding the trailing edge of the work-sheets tight against the platen for typing on the extreme lower edge thereof.

It is also usual to have the lower card, the one that lies nearest to the platen after insertion, made of thin flexible cardboard

and, to permit legible printing and typing on the card, to use cardboard with a slightly glazed surface. This glazed surface coming in contact with the smooth platen will 5 render the comparatively thick pack liable to "skew" or twist in the machine during line-spacing, thus throwing the lines of typed matter on the forms out of parallelism. Another object of our invention is 10 to provide means for not only gaging and squaring the card-pack upon insertion into the machine, but for retaining it in that squared or trued position during the entire typing operation. The use of cardboard 15 for one of the cards of the pack also brings up the problem of binding the pack around the platen and means are provided for accomplishing this object so that feeding means may retain it in close proximity to 20 the platen for typing matter thereon.

It is desirable and usual to have a plurality of writing-lines on the forms, and to have these writing-lines extend to the very bottom of the cards. Still another object 25 of our invention is to provide feeding and holding means that will retain the card-pack close to the platen in its "squared" position, holding it both above and below the printing-point, until the very last writing-lines on the forms have received typed 30 matter.

Other features and advantages will hereinafter appear.

In the accompanying drawings,

35 Figure 1 is a plan view of the carriage of a typewriting machine with our mechanism attached thereto, the parts being in normal position to begin a typing operation on a card-pack, which is shown inserted in 40 the machine with the first writing-line of the form at the printing-point.

Figure 2 is a front elevation of the same mechanism shown in Figure 1 except that the card-pack has been advanced to bring 45 the last writing-line of the form to the printing-point.

Figure 3 is a plan view of the carriage of a typewriting machine with our mechanism attached thereto, the platen-swing 50 frame being displaced to show the method of inserting the leading edge of a card-pack into the machine.

Figure 4 is a longitudinal, cross-sectional view of the leading edge of a card-pack 55 showing how the holes in some of the cards are protected by stiff paper disks, and how a cord is threaded through a hole in another of the cards.

Figure 5 is a view of the leading edge of 60 a card-pack and further discloses its construction.

Figure 6 is a cross-sectional view through the carriage of the machine on the line 6—6 of Figure 2, the parts being in the position 65 shown in Figure 3.

Figure 7 is a cross-sectional view similar to Figure 6 except that the parts are in the position shown in Figure 1.

Figure 8 is a fragmentary, cross-sectional view of the platen showing the relative position of the Y-shaped clips that form a part of the pack-holding mechanism.

A platen 9 is mounted on a platen-shaft 10, journaled in a swing-frame 11 which includes a front paper-table 12 and is mounted in a movable carriage 13. The carriage 13 includes a rear paper-table 14, which cooperates with feed-rolls 15 in guiding work-sheets underneath and around the platen 9, and an auxiliary-front paper-table or deflector 14^a, the use of which will be more fully explained later. The platen 9 is rotated by means of platen-knobs 16 through spur-gears 17, spur-pinions 18, and spur-gears 19 which are fastened to the platen-shaft 10. The swing-frame 11 is retained, with the platen in normal position, by hooks 20 which are mounted on the carriage 13 and which engage pins 21 on the swing-frame 11. Journaled in the carriage 13 is a transverse shaft 22 on which are mounted brackets 23, which carry a transverse shaft 24, and brackets 25, which carry a transverse shaft 26. A feed-roll-frame 27, made up of two parallel end members 28 and 29 and two parallel transverse shafts 30 and 31, which carry supplemental feed-rolls 32, 33 and 34, and Y-shaped clips 35 and 36, is mounted on brackets 37 on the transverse shaft 22. The feed-rolls 32 and 33 are fastened to the shaft 30, the Y-shaped clips 35 and 36 are fastened to the shaft 31, and the feed-roll 34 is loosely mounted on the latter shaft on a collar 34^a. Arms 38 on the brackets 37 engage adjacent flat, cam surfaces on the transverse shaft 26 which is actuated by feed-roll releasing mechanism, not shown, to release the feed-rolls 32, 33 and 34, and the Y-shaped clips 35 and 36 from contact with the platen when work-sheets are being inserted into the machine in the ordinary manner. The end members 28 and 29 are preferably made of spring steel, and have journal-boxes 39 mounted thereon to receive the transverse shafts 30 and 31, the ends 110 of which are tapped to receive retaining screws 40.

While this construction may be changed, without departing from our invention, it is the preferred form and allows the shaft 30 120 to rotate with the feed-rolls 32 and 33, and allows the feed-roll 34 to rotate independently of the shaft 31, which, in turn, may have rotative movement with the Y-shaped clips 35 and 36.

The end members 28 and 29 project below the shaft 31 and are caught behind the shaft 24, as at 41 and 42, in the manner shown in Figures 6 and 7, thus holding the feed-roll-frame 27, when it is in normal position, 130

under additional tension with the feed-rolls 32, 33 and 34 pressing against the platen 9. The Y-shaped clips 35 and 36 are also preferably made of spring steel and have downwardly-projecting legs 43 and 44 which are caught behind the transverse shaft 26, as at 45 and 46, in the manner shown in Figure 8, so that, when the feed-roll-frame 27 is in normal position, the clips 35 and 36 will also be under additional tension against the platen 9. It will be noted here that the printing-point 47 of the machine lies between the feed-rolls 32 and 33 and the tops of the Y-shaped clips 35 and 36.

15 It will be seen from the above description that the feed-roll-frame 27, including the feed-rolls 32, 33 and 34, and the Y-shaped clips 35 and 36, is movably mounted as a unit on the brackets 37, and that it 20 will move away from the platen 9 as a unit when actuated by the feed-roll releasing mechanism, which simultaneously moves the feed-rolls 15 from engagement with the platen 9. The feed-roll-frame 27 can, of course, also be moved up to the platen by the releasing mechanism, after which the various feed-rolls and clips, except the feed-rolls 15, will be brought under still greater tension than that exerted by the releasing 25 mechanism by means of the independent spring-means described. It is important that this increased holding power of the feed-rolls 32, 33 and 34 and the Y-shaped clips 35 and 36 be fully appreciated as these 30 members play an important part in accomplishing the objects desired.

Mounted on the rear paper-table 14 are duplicate adjustable paper-guides 48 having bodies 49 and upturned edges 50. Another 35 set of right and left paper-guides 51, which have bodies 52, upturned edges 53 and wings 54, are adjustably mounted on the front paper-table 12. By referring to Figures 3 and 5, it will be seen that the paper-guides 48 and 51 co-operating with the paper-tables 12, 14 and 14^a form a chute, when the swing-frame 11 is brought forwardly and downwardly to displace the platen 9 upwardly from the feed-rolls 15, 40 for inserting the card-pack into the machine. Figure 3 particularly shows how the card-pack is "squared" with the platen 9, by means of the paper-guides 48 and 51, before the platen 9 is lowered. Figures 1 and 7 show how the paper-guides 48 and 51 retain the card-pack in its "squared" position when the platen is lowered. A long, narrow card-pack 55, has, in this instance, an outer or top card 56 made of comparatively heavy 45 paper with filing holes punched near the leading edge. Second and third cards 57 and 58 are made of somewhat lighter paper and have single filing holes in the center, near their leading edges, which are protected by tough paper disks 59 and 60. A bottom card 61 is made of a light-weight, flexible card-board and has a similar filing hole protected by similar tough paper-disks 62, and, in addition, has a cord 63 threaded through the hole. The cards 56, 57, 58 and 61 have 50 similar forms printed thereon, the writing-lines of which extend to the very bottoms of the cards, and are fastened together near their leading edges by wire staples 64 which hold the forms in registration with one 55 another. It will be appreciated that the leading edge of the pack 55 will be quite thick due to the paper used for some of the cards and the presence of the wire staples 64 and the cord 63.

It is understood, of course, that the pack may be interleaved with carbon-sheets or the sheets of a carbon-pack, that it may be of any desired dimensions provided it will fit into the machine, that the number of 60 cards may vary as may their weights, colors and textures, that any suitable forms may be printed on them, that any or all of them may be provided with protected holes, or 65 cords, or both, or be left plain without holes or cords at all, or may have a plurality of 70 such holes, and that any suitable fastening 75 means may be employed.

In operation, the typist releases the hooks 80 and lifts the swing-frame 11 forwardly and backwardly until it assumes the position shown in Figures 3 and 6. The upstanding edges 50 and 53 of the paper-guides 48 and 51 now form the sides of a sectional chute, the top of which is the front paper-table 12, 85 and the bottom of which is the flat surface of the rear paper-table 14, supplemented by the auxiliary-front paper-table 14^a, and the longitudinal axis of which is at right angles to the longitudinal axis of the platen 9. Inserting the leading edge of a card-pack 90 95 between the upstanding edges 50 of the paper-guides 48, it is pushed forward underneath the platen and over the feed-rolls 32 and 33, in a straightened condition, until the leading edge strikes the inclined surface of the auxiliary-front paper-table or deflector 14^a and until one of the corners strikes one of the wings 54, which guides it between 100 the upstanding edges 53 of the paper-guides 51 and over the front of the carriage 13. In this position the writing-lines on the 105 forms are parallel to the longitudinal axis of the platen 9. The chute thus serves a double purpose; that of facilitating the 110 insertion of the card-pack 55 into the machine, and that of "squearing" the card-pack with the platen 9 simultaneously with the act of insertion. It will be noted that 115 in raising the platen 9, the feed-rolls 15, 32, 33 and 34 and the Y-shaped clips 35 and 36 have all been disengaged without operating the feed-roll displacing mechanism; in fact,

that mechanism need only be employed when the machine is being used for ordinary work.

It will also be noted that after the operation has progressed this far, the pack 55 is left in a straightened position, due to the cardboard, and rests on the horizontal surface of the rear paper-table 14 and the auxiliary-front paper-table 14^a.

10 The swing-frame 11 is now brought to the normal position shown in Figures 1, 2 and 7, when the hooks 20 will automatically engage the pins 21. Following the action of the platen in its descent, it will be noted 15 that after striking the pack 55, it bends it downwardly around the feed-rolls 32 and 33, and, as the descent continues, the feed-rolls 32 and 33 are placed under greater and greater tension, until, when the descent is 20 finished, the pack is held closely against the platen, both above and below the printing-point, and is ready to be typed upon. It will also be noted that, during the entire descent of the platen to normal, the pack 55 25 has been held in its "squared" position by the paper-guides 48 and 51. The feed-rolls 15 will now be placed, under ordinary tension, in contact with the card-pack 55, and the feed-rolls 32, 33 and 34 and the Y-shaped 30 clips 35 and 36 will be placed under additional tension by virtue of the spring-steel construction already described. The pack 55, as now held, cannot "skew" or be fed other than in the desired manner. The 35 parts have now reached the positions shown in Figure 7, and it will be seen that the chute mentioned above has been disrupted by the platen-returning operation, and now takes the form of two chute sections, one of which 40 is formed by the rear paper-table 14 and the paper-guides 48, on the entry side of said platen, and the other of which is formed by the front paper-table 12 and the paper-guides 51, on the delivery side of said platen. The chute, as now split into sections, will continue to function as before in 45 retaining the pack 55 in its "squared" position, with reference to the platen, as the pack 55 is advanced by line-spacing during 50 the typing operation which follows.

The typist now types the required matter on the writing-lines of the form, advancing the card-pack 55 with the usual line-space mechanism until the trailing edge of the pack 55 passes by the paper-guides 48. The additional pressure, already mentioned as being applied to the feed-rolls 32, 33 and 34 and the Y-shaped clips 35 and 36, is now 55 useful in co-operating with the paper-guides 51 in keeping the card-pack 55 from "skewing."

Additional matter is typed on succeeding writing-lines until the trailing edge of the card-pack 55 has passed by the feed-rolls 15 and 34, the tension of the remaining

engaged feed-rolls and clips always holding the card-pack 55 in position. The last writing-line on the forms is now opposite the printing-point 47, and the upwardly-extending fingers of the Y-shaped clips 35 and 36 70 keep the trailing edge of the card-pack 55 straight and tight against the platen 9, while the remaining feed-rolls 32 and 33 still prevent "skewing" until matter has been typed on that last writing-line. The 75 card-pack 55 is now pulled from the machine with the fingers, showing every writing-line thereon parallel to the others. The swing-frame 11 is again released and raised, and the entire operation repeated for the 80 next card-pack.

Variations may be resorted to within the scope of the invention, and portions of the improvements may be used without others.

Having thus described our invention, we 85 claim:

1. In a typewriting machine, the combination of a platen, main feed-rolls, means for moving the platen in its typing position away from the feed-rolls to make room between the platen and rolls for introducing work-pieces beneath the platen and over the rolls, supplemental feed-rolls at the front of the platen and located above a horizontal plane drawn through the axis of rotation of 90 the platen in its typewriting operating position for pressing the work-piece against the platen, releasing mechanism for the feed-rolls, and resilient means effective between the releasing mechanism, platen and said supplemental feed-rolls when the releasing mechanism has been operated to move said supplemental rolls against the platen in its typewriting operating position for pressing 95 said supplemental rolls under additional tension against the platen in its typewriting operating position. 100

2. In a typewriting machine, the combination of a platen, main feed-rolls, means for moving the platen in its typing position 110 away from the feed-rolls to make room between the platen and rolls for introducing work-pieces beneath the platen and over the rolls, supplemental feed-rolls at the front of the platen and located above the horizontal plane drawn through the axis of rotation of 115 the platen in its typewriting operating position for pressing the work-piece against the platen above the printing line, fingers at the front of the platen for pressing the work-piece against the platen below the printing line, releasing mechanism for the feed-rolls and said fingers, and resilient means effective between the releasing mechanism, platen, said supplemental feed-rolls and fingers when the releasing mechanism has been operated to move said supplemental rolls and fingers against the platen 120 in its typewriting operating position for pressing said supplemental rolls and fingers 125 130

under additional tension against the platen in its typewriting operating position.

3. In a typewriting machine, the combination of a platen, main feed-rolls, means for moving the platen in its typing position from the feed-rolls to make room beneath the platen and feed-rolls for introducing work-pieces beneath the platen and over the rolls in straight-line condition, a paper-table at the rear of the platen for supporting the work-pieces at their rear, a support at the front of the platen for supporting the work-pieces at their front as projected forwardly from the rear paper-table in straight-line condition beneath the platen and over the main feed-rolls, the top of the rear table and said support being lower than the platen in its raised position, but higher than the platen in its typewriting position, an upwardly-inclined deflector piece at the rear of said support for directing the sagging ends of the work-pieces upwardly onto the top of said support, and supplemental feed-rolls at the front of the platen and located in a horizontal plane above the axis of the platen in its typing position for pressing the work-pieces against the front of the platen as the latter is lowered to its typewriting position, bending the work-pieces around it in its descent to its typewriting position.

4. In combination, a typewriting machine having a carriage, a platen and means for feeding work around said platen, a swing frame on said carriage, said platen being mounted in said swing frame and being displaceable upwardly from said feeding means, a paper-table on said swing frame, a second paper-table on said carriage, side guiding means on both said paper-tables, said paper-tables and guiding means cooperating to define a discontinuous chute when said platen is displaced to permit insertion of the work beneath the raised platen in substantially flat condition with the writing lines substantially parallel to the longitudinal axis of the platen, said guiding means being adjustable to accommodate work of different widths, and an auxiliary front paper-table on said carriage having a downwardly inclined portion to guide the leading edge of the work upwardly in both normal and displaced positions of said platen.

5. The combination, a typewriting machine having a carriage, a platen and means for feeding work around said platen, a swing frame on said carriage, said platen being mounted in said swing frame and being displaceable upwardly from said feeding means, a paper-table on said swing frame, a second paper-table on said carriage, side guiding means on both said paper-tables, said paper-tables and guiding means co-operating to define a discontinuous chute

when said platen is displaced to permit insertion of the work beneath the raised platen in substantially flat condition with the writing lines substantially parallel to the longitudinal axis of the platen, a first supplemental feeding means supported under pressure against the front of said platen above the striking point, and a second supplemental feeding means supported under pressure against the platen below said striking point, both of said supplemental feeding means being co-operative with the guiding means of said first-named paper-table to maintain the work squared with and in close proximity to said platen after the trailing edge of the work has passed out of control of the guiding means of said second-named paper-table.

6. In combination, a typewriting machine having a carriage, a platen and means for feeding work around said platen, a swing frame on said carriage, said platen being mounted in said swing frame and being displaceable upwardly from said feeding means, a paper-table on said swing frame, a second paper-table on said carriage, side guiding means on both said paper-tables, said paper-tables and guiding means co-operating to define a discontinuous chute when said platen is displaced to permit insertion of the work beneath the raised platen in substantially flat condition with the writing lines substantially parallel to the longitudinal axis of the platen, said chute defining a substantially straight path during displacement of said platen and providing entry and delivery guides when said platen is in normal writing position, a first supplemental feeding means supported under pressure against the front of said platen above the striking point, a second supplemental feeding means supported under pressure against the platen below said striking point, and holding means operatively located between said striking point and said second supplemental feeding means, said holding means being co-operative with said first supplemental feeding means to maintain the work squared with and in close proximity to said platen after the trailing edge of the work has passed said second supplemental feeding means.

7. In a typewriting machine, in combination, a carriage, a platen, means for feeding work around said platen, means for displacing said platen upwardly from said feeding means to permit the introduction of a substantially flat piece of work beneath said platen, a supplemental feed-roll frame mounted on said carriage, said feed-roll frame including substantially parallel top and bottom members, a plurality of feed-rolls operatively located on said top and bottom members, and a plurality of paper-clips on said bottom member, whereby said sup-

plemental feed-roll frame is co-operative with said platen during return of the latter to normal position to effect bending of the work about said platen and at all times 5 maintain said work in substantially smooth condition about said platen.

8. In a typewriting machine, in combination, a carriage, a platen, means for feeding work around said platen, means for displacing said platen upwardly from said feeding means to permit the introduction of a substantially flat piece of work beneath said platen, a supplemental feed-roll frame mounted on said carriage, said feed-roll 10 frame including a top shaft located substantially above the striking point, a bottom shaft located substantially below the striking point, said shafts being substantially parallel to each other, substantially parallel 15 end pieces resiliently secured below said bottom shaft, a pair of feed-rolls on said top shaft, a plurality of paper-clips on said bottom shaft, and a feed-roll on said bottom shaft between said paper-clips, whereby said 20 shafts exert pressure toward and are co-operative with said platen during return of the latter to normal position to effect bending of the work about said platen and at all times maintain the work in substantially 25 smooth condition about said platen.

30 9. In a front-strike typewriting machine, the combination with a platen and a carriage, of means for displacing said platen upwardly to permit laying a work piece or pack beneath said platen, said carriage comprising means to serve as front and rear supports for said work-piece, and means to co-operate with the front of said platen, during the descent of the latter, to grip said work- 35 piece, so that, during the remainder of the descent of said platen, said work-piece is wrapped around the front and bottom of 40

said platen preparatory to being typed upon.

10. In a front-strike typewriting machine, the combination with a revoluble platen and means at the under side thereof to co-operate therewith for feeding a work-piece around said platen, of work-guides to bear against the front of said platen below and above the printing-point, said platen being displaceable upwardly to permit the introduction of a straightened work-piece between said platen and the upper work-guide, said work-guides being so placed that the platen, in descending, forces the work-piece to become wrapped around said platen by the co-operation of all of said guides. 45

11. In a front-strike typewriting machine, the combination with a revoluble platen, a carriage, and means to co-operate with the under side of said platen to feed a work sheet or sheets through the machine, of means to displace said platen upwardly to permit the introduction of a work sheet or sheets below said platen, rotating means mounted on said platen and said carriage to render said platen rotative whether in displaced or normal position, and bending means located in front of said platen above the printing-point, and occupying a position beneath said elevated platen, so that said work sheet or sheets may be inserted and bent between said bending means and said elevated platen, said bending means serving to co-operate with said platen, as the latter descends, to bend said work sheet or sheets around said platen, said bending means then co-operating with said co-operative feeding means to hold said work sheet or sheets in smooth condition around said platen preparatory to being typed upon. 50
